REINFORCED PILE AND METHOD OF
MAKING THE SAMEThorwald H. Hansen, Brighton, Trinidad, British
West Indies

Application November 3, 1938, Serial No. 238,523

12 Claims. (Cl. 61—54)

The present invention is directed to the reinforcement of telegraph and telephone poles, railroad trestles, piles in pier construction, and the like. More particularly, the invention is directed 5 to the treatment of such piles and the like already in place and embodied in structures or is adaptable to a plant for the pre-treatment thereof before being placed in structures.

As is well known, piles in various structures 10 are subject to deterioration and erosion. In order to delay such destruction, it has been customary to impregnate the piles with liquid preservatives, but the use thereof merely delayed the deterioration. It was customary to replace 15 eroded piles in a structure such as a pier by removing those in bad condition and replacing the same. This necessitated frequent replacements of a portion of the piles with the result that at each repair, the pier or the like was tied up.

20 In the final analysis, in many cases piles had to be replaced every six or seven years and methods were proposed to increase the life thereof. For example, there was a proposal to reinforce eroded piles by attaching at the eroded portion 25 logs or similar members which were bolted together and were secured by spikes or otherwise to the piles. This was an expensive method and the effectiveness was only moderate. It was difficult to apply to piles in a pier for the reason 30 that it was necessary to work under water.

It has also been proposed to strengthen eroded piles by enclosing the eroded portion by a jacket of concrete or the like. In such case, it was necessary to build a form around the pile and 35 make that form water-tight. Thereafter, the water was pumped out from the inside of the form and concrete was poured in place. This was effective, but for most purposes the cost was much too high to be economical. It has also 40 been attempted to form a concrete jacket around piles without the pumping out of the water by merely placing the form around the pile and pouring the concrete into the water. This was not at all successful, since salt water has a deteriorating 45 influence on the concrete and the pouring of the concrete into the water caused a separation of the concrete into heavier and lighter strata, thus destroying the strength thereof.

It has also been proposed to encase piles with 50 a concrete jacket at the time they are being driven into place. This method contemplated the placing of a form about a portion of a pile, pouring the concrete into the form, and then by means of a pile driver, driving the same into 55 its final position while the concrete was still

plastic. This had numerous disadvantages, in that one could not determine in advance the depth to which the pile would be driven and therefore the jacket was very likely to be in the wrong place. Special concrete castings were necessary in order to seal the bottom of the form into which the concrete was cast, necessitating a considerable amount of labor for fastening said castings into place. This method could not be used on piles after they are placed in a structure and this process also tied up the structure so that during repairs it could not be used.

The present invention is intended to eliminate the difficulties and disadvantages of prior structures and to provide a reinforcement for piles and 10 the like and a method whereby the same may be produced which is simple, inexpensive, does not require skilled labor, does not require under water work, which does not require special forms 15 or molds, and which can be accomplished with 20 standard materials and without special equipment.

In practicing my invention, I provide a form 25 into which the concrete is to be poured, said form being of ordinary sheet metal, bent to the proper shape, and the edges thereof bolted together to complete the form. It is sunk to the proper depth and care need not be taken to make the same water-tight. By suitable means, sufficient 30 fresh water is caused to flow into the bottom of the form, thus displacing the salt water normally present around piers. Then a slurry of 35 cement and water, as thick as can be conveniently poured, is run into the bottom of the form for a suitable depth, usually from one to three feet, displacing the fresh water upwardly and out of the top of the form. Thereafter, concrete 40 is poured into the bottom of the form, displacing the slurry of cement and water upwardly. The concrete is poured into the form until all of the 45 slurry has overflowed out of the top thereof.

By this method there has been eliminated every possibility of the mixing of salt water with the concrete and at the same time, has eliminated the necessity of making special forms which are 50 water-tight, and has also, of course, eliminated the necessity of pumping water from the inside of the form. For various jobs where the length of the pile to be protected varies, the same forms 55 may be used since they are made of standard size sheet metal welded together in a suitable number of lengths for the specific purpose. The same molds may be used for practically all jobs and no under water work is necessary.

By reason of the use of a cement slurry prior 55

to the introduction of concrete, several very important advantages are obtained. The slurry lines the interior of the form and also coats the surface of the pile. After the concrete is poured, these coatings remain in place and become integral with the concrete. The outside film of cement forms a case around the concrete which is very hard and dense and offers high resistance to mechanical erosion. The inner film of cement adheres very strongly to the wood as well as to the concrete and makes a union which is so tight that the concrete cannot be removed without tearing away the wood with it.

As a further advantage of the use of this method, tamping or otherwise vibrating the plastic concrete is unnecessary, as the cement completely fills the interstices of the concrete and assures a dense and hard product.

In the accompanying drawings, constituting a part hereof, and in which like reference characters indicate like parts,

Fig. 1 is a side elevational view of a pile in place, showing an eroded portion;

Fig. 2 is a view similar to Fig. 1, showing reinforcements in place thereon as one of the first steps in the operation;

Fig. 3 is a view showing the next step of the operation;

Fig. 4 is a similar view showing the concrete jacket in place;

Fig. 5 is a side elevational view, diagrammatic in character, showing the first step of the present process;

Figs. 6 and 7 show successively two additional steps of the operation; and

Fig. 8 is a cross-sectional view taken along the line 8—8 of Fig. 7.

As shown in Fig. 1, various marine borers such as toredo, limnoria, martesia and others, attack the pile 1, forming an eroded portion 2 with the various marine borers traveling upwardly and downwardly. Erosion takes place not only at or above the low water-line 3, but may continue up to and above the high water-mark 4 and may go down to the mud-line 5, or even somewhat lower. In all cases, it has been found that when protection is given from a point somewhat above the high water-line 4 to a point somewhat below the mud-line 5, complete elimination of the effect of borers is obtained.

As a first step in the operation, there are provided reinforcing staples 6 of any suitable character, often being rectangular in cross-section and of adequate size, having the ends 7 thereof inturned at right angles and sharpened to a point to form spikes. As shown in Fig. 2, the staples are driven in until they are flush with the outer periphery of the piles and at different levels, so that the spikes 7 do not form a ring in a single plane. There is usually also provided a reinforcing mesh 8, surrounding the pile at the proper level and over the desired portion to be jackedeted. The concrete 9 extends over the entire area covered by the wire mesh or the like 8, and usually a short distance above and below the same.

In operating the process special reference is had to Figs. 5, 6 and 7, showing the various stages of the operation of the process. The pile 1 is first prepared by scraping off the barnacles and other marine growth, and a form 10 placed around the same. The form consists of a series of pieces of sheet metal, usually steel, welded together end to end to give the desired length. Along the free edges thereof are provided angular mem-

bers 11 which are welded to the edges, as shown at 12. The outer sides of members 11 are provided with cooperating flanges 13 having openings for the reception of bolts 14 to hold the same together. The form is placed in position around the pile, the bolts 14 are secured in place and by means of a jet, the silt at the mud-line around the pile is washed away for a depth of about one foot and the form is lowered into this depression and centered in place. The bottom 10 may be sealed up in a very simple manner if it is found there is some leakage by the piling of silt around the bottom thereof.

A pipe 15 having a funnel 16 secured to the upper end is lowered into the form so that the bottom opening 17 of pipe 15 is practically at the bottom of said form. The pipe 15 operates in the side chamber formed by angular members 11.

Everything now being in place, the operation is started by pouring fresh water into the funnel 16, displacing salt water upwardly and out over the top edge of the form. As soon as this is completed, a slurry 18 of cement and water is introduced into the funnel 16, such slurry being usually of about equal parts of water and cement. A depth of 1 to 2 or 3 feet of slurry is obtained in the bottom of the form. Thereafter, as shown in Fig. 6, a suitable concrete mixture 19 in plastic state is introduced into the pipe 15, emerging from the bottom 17 thereof and displacing the slurry 18 upwardly toward the top of the form. The pouring in of concrete is continued until, as shown in Fig. 7, all of the slurry has been displaced and the entire form is filled with concrete. The pipe 15 is then removed and the concrete allowed to set, after which the forms are removed. By the term "concrete" as used herein it is intended to include the compositions commonly so-called, in which there is cement and the usual fillers, such as sand, gravel, crushed rock, and the like.

It is, of course, understood that reinforcements such as shown in Figs. 2 and 3 may be, and usually are, included in the final jacket. In such case, the wire mesh 8 may be centered in any known manner as by welding inwardly directed metal pieces to properly center the mesh, or by introducing next to the pile a number of pipes of the correct diameter to act as a guide and the mesh is then rolled around the pipes. After the mesh has been wired in place, the pipes may be removed.

The present method may be used for the repair of piers and other marine structures without tying up the structure during the repair period. Furthermore, it is adapted to repair piles which are so far gone as to require replacement and the cost of such repair need not exceed one-half of the cost of replacement of such piles. As the result of the present method, piles not only are repaired, but they will now last for many times the normal life of a pile in the particular locality.

Although I have described my invention setting forth a single embodiment thereof and outlining the use thereof in the repair of piers and similar structures, the invention is adapted for many other uses. For example, it may be applied in the repair of railroad trestles, telegraph and telephone poles and various other structures. The principles of my method are applicable to situations such as the building of piers or foundations in water or in situations where water is encountered. In many cases, the present method avoids the necessity of building expensive coffer-

dams to keep out water. Therefore, the present method is one of general application and is not confined to the repair of piles or the like.

Numerous variations in the details of procedure may, of course, be made within the principles of the present invention. Different types of reinforcing may be used or reinforcements may in certain cases be entirely dispensed with. The forms used in my method may be of different types, although those described above are deemed to be simple and effective. The forms may be provided with a coating of oil or the like on the interior surface thereof in order to avoid sticking of the cement to the surface, and also to render it easy to remove the forms. The slurry 18 has been described above as being merely a mixture of water and cement. However, other ingredients may be added thereto, as for instance, small amounts of sand, gravel or the like may be added, which will not interfere with the intended operation of the slurry, the purpose being to have the relatively heavy cement slurry settle to the bottom, which results in excellent concrete from the bottom upward. Furthermore, other substances than cement may be used in order to give the same effect as described herein, it being desirable to use a material which will penetrate and adhere to the fibers of the wood. The thickness of the concrete jacket may vary but, for the sake of economy, I usually provide a thickness of 2" or less, the side chamber for the introduction of the concrete rendering this possible and also a longitudinal, integral, concrete reinforcing rib 20 along the side of the jacket.

35 These and other changes in the details of operation may be made within the spirit of my invention, the scope of which is not to be limited except by the character of the claims appended hereto.

40 What I claim is:

1. A method of casting concrete which comprises providing a form, pouring a cement slurry in the bottom of the space enclosed by said form, introducing plastic concrete beneath the surface of said slurry and displacing the same upwardly, said slurry floating on the surface of said concrete.

2. A method of casting concrete which comprises providing a form, positioning said form in a water-containing area, pouring a cement slurry in the bottom of the space enclosed by said form, introducing plastic concrete beneath the surface of said slurry and displacing the same upwardly, said slurry floating on the surface of said concrete.

3. A method of casting concrete which comprises providing a form, positioning said form in a salt water-containing area, introducing fresh water into said form to displace salt water, pouring a cement slurry in the bottom of the space enclosed by said form, introducing plastic concrete beneath the surface of said slurry and displacing the same upwardly, said slurry floating on the surface of said concrete.

4. A method of strengthening eroded wooden piles which comprises providing a form for concrete, surrounding the pile with the same over the area to be strengthened, pouring a cement slurry into the bottom of the same, and introducing plastic cement beneath the surface of said slurry. 5

5. A method of strengthening eroded wooden piles located in salt water which comprises providing a form for concrete, surrounding the pile with the same over the area to be strengthened, 10 introducing fresh water into said form to displace salt water, pouring a cement slurry into the bottom of the same, and introducing plastic cement beneath the surface of said slurry.

6. A method of strengthening eroded wooden piles which comprises providing a form for concrete, surrounding the pile with the same over the area to be strengthened, pouring a cement slurry into the bottom of the same, and introducing plastic cement beneath the surface of said 15 slurry along a side of said form.

7. An article comprising a wooden pile eroded over a portion of its length, a thin jacket of concrete containing cement and filler surrounding and filling said eroded portion, a longitudinal 20 rib of concrete integral with said jacket, and metal reinforcements in said concrete. 25

8. An article comprising a wooden pile eroded over a portion of its length, a thin jacket of concrete containing cement and filler surrounding 30 and filling said eroded portion, and metal staples bridging the eroded portion and anchored in said pile at both ends of said staples and embedded in said jacket. 35

9. An article comprising a wooden pile eroded over a portion of its length, a thin jacket of concrete containing cement and filler surrounding and filling said eroded portion, and metal staples having a longitudinal member bridging the eroded portion, the ends thereof being provided with 40 inturned spikes anchored in said pile and embedded in said jacket. 40

10. An article comprising a wooden pile eroded over a portion of its length, a thin jacket of concrete containing cement and filler surrounding 45 and filling said eroded portion, and metal staples bridging the eroded portion and anchored in said pile at both ends of said staples and embedded in said jacket, and annular metal mesh surrounding said pile and also embedded in said 50 jacket. 50

11. An article comprising a wooden pile eroded over a portion of its length, a thin jacket of concrete containing cement and filler surrounding and filling said eroded portion, metal reinforcements in said concrete, and a case of pure cement 55 only on said jacket.

12. An article comprising a wooden pile eroded over a portion of its length, a thin jacket of concrete containing cement and filler surrounding 60 and filling said eroded portion, a film of pure cement only adhering to the pile and a film of pure cement only on the outside of said concrete. 65
